CONCRETE FORM AND REINFORCEMENT
RETAINING MEANS

Samuel S. Colt, Orange, N. J.

Application April 27, 1936, Serial No. 76,580

9 Claims. (Cl. 25—131)

This invention relates to concrete form retaining means of the general type and kind disclosed in my prior Letters Patent of the United States No. 2,014,080, dated September 10, 1935; and this invention has reference, more particularly, to form wall retaining means arranged to include a novel means for also supporting concrete reinforcing rods or bars in proper position within the form interior, preparatory to casting concrete into the form.

The invention has for an object to provide form wall engaging means cooperative with tie means and spacer means, whereby the form walls are supported in desired predetermined spaced apart or spread relation against both outward and inward collapse, novel means being also provided in connection with said spacer means for supporting reinforcing rods or bars in predetermined position within the form and in desired spaced relation to a form wall, preparatory to casting concrete into the form and in imbedding relation to said reinforcing rods or bars.

Other objects of this invention, not at this time more particularly enumerated, will be understood from the following description of the same.

Illustrative embodiments of this invention are shown in the accompanying drawings, in which:

Fig. 1 is a fragmentary vertical cross section through a form showing the wall retaining relations of the supporting, tying and spacing means therefor and the means for holding inserted reinforcing rods or bars; Fig. 2 is a horizontal section through the same, taken on line 2—2 in said Fig. 1; Fig. 3 is a similar horizontal section, showing the use of auxiliary form wall spacing means.

Fig. 4 is a perspective view of a spacer device having means to embrace and position one or more reinforcing rods or bars within the form interior.

Fig. 5 is a horizontal section, similar to that of Fig. 2, but showing a modified arrangement of the form wall tying and spacing elements of the wall retaining means; and Fig. 6 is a fragmentary vertical section, taken on line 6—6 in Fig. 5, but drawn on an enlarged scale.

Similar characters of reference are employed in the above-described views, to indicate corresponding parts.

Referring to the drawings, the reference character 10 indicates the opposed walls of a concrete form to the exterior faces of which are applied, in suitably spaced apart relation, the uprights or battens 11, across the exteriors of which extend the spaced walers 12.

The form wall retaining means, in one arrangement, as utilized to extend through the form walls and form interior, comprises a unitary tie-rod 13. Cooperative with each form wall is a wall penetrating sleeve. In preferred construction, each sleeve comprises a longitudinal split to provide separable members, which, for convenience of description, will be designated a lower sleeve member 14 and an upper sleeve member 15. These sleeves are engaged over and around said tie-rod 13, whereby the latter extends axially therethrough. The inner end portion of the lower sleeve member 14 is formed to provide a tapered section 16 which starts flush from the exterior surface thereof. The inner end portion of the upper sleeve member 15 is also formed to provide a tapered inner end section 17, which, at its juncture with the exterior surface thereof, is eccentric thereto so as to provide a stop-shoulder 18 engageable with the inner face of a form wall 10. When the sleeve members 14—15 are assembled together, their tapered sections 16—17 provide the sleeve with a conical interior end portion. At their outer ends, said sleeve members 14—15 are usually provided with laterally projecting perforate or indented ears or lugs 19, through one or both of which may be passed a fastening nail 20 adapted to be driven into the form wall with which the sleeve is associated, to thereby hold the sleeve members, and especially the lower sleeve member 14 against accidental outward displacement from its operatively arranged relation to the form wall served by the sleeve.

The form walls 10 are provided with through openings 21 of a diameter sufficient to receive and fit the circumference of the outer portions of the sleeves as formed by the assembled sleeve members 14—15.

Cooperative with the sleeve and tie-rod is a spacer element 22 having a longitudinal bore 23 through which the tie-rod 13 extends. In assembling the form retaining means, the tie-rod 13 is passed through the form walls and form interior from one exterior side of the form to the other exterior side thereof, and the spacer element 22 is slid onto the tie-rod 13 so as to ride upon the portion thereof which lies intermediate the form walls 10. Since the diameter of the tie-rod 13 is considerably less than the diameters of the form wall openings 21, the tie-rod will rest temporarily upon the bottom sides of said openings 21, thus leaving sufficient space for the insertion thereover, from the exterior sides of the form walls, and through said openings 21, 55

of the upper sleeve member 15 and their stop shoulders 18, whereby the latter may be positioned to engage or abut the interior faces of form walls 10. After the insertion of said upper 5 sleeve members 15, the lower sleeve members 14 may be engaged beneath the tie-rod 13 and then inserted through the form wall openings 21 until registered with the upper sleeve members 15, whereby the latter are moved laterally in the 10 openings 21 to position the stop shoulders 18 thereof for engagement with the inner faces of the form walls 10.

In order to assure the spacing apart of the 15 form walls 10 at a predetermined distance, according to the thickness of concrete wall desired to be produced, the length of the form penetrating tapered end portions 16-17 of the sleeve members 14-15 are suitably predetermined, as is also the length of the spacer element 22. For example, said tapered end portions 16-17 of the sleeve members 14-15 may be furnished with a length of three inches, and the spacer element 22 of a length of two inches, whereby when these parts are arranged end to end as assembled between the form walls, said 25 walls will be spread in a spaced relation of eight inches so that a cast wall of the latter dimension in thickness will be reproduced. It will be understood, that these part dimensions are subject to a wide range of variation in dimension, the 30 above recited dimensions being mentioned only by way of example. It will also be understood, that where thicker walls are desired to be made, auxiliary spacing sleeves 24 of suitable length 35 may be employed on the tie-rod 13 and between a sleeve device 14-15 and the primary spacer element 22, as shown in Fig. 3.

After the tie-rod, sleeves and spacer element or elements have been assembled and put in place, flanged keeper nuts 25, or any other suitable form of locking-up means, may be applied to the exteriorly projecting ends of the tie-rod 13. If keeper nuts 25 are employed, the end portions of said tie-rod 13 are threaded to receive 45 the same, so that the nuts may be screwed home on the tie-rod ends to engage their flanged side in abutting relation to the walers 12, and thus press home the form walls 10 against the stop shoulders 18 of the sleeves 14-15, so that the said 50 walls are firmly secured in desired mutually spaced apart and fixed relation against both inward and outward displacement.

It being frequently desirable to insert within the form interior upstanding steel rods or bars 55 to be imbedded in the concrete mass of the wall as reenforcing therefor, I have devised in combination with the spacer element 22 novel means for supporting such rods or bars in upstanding relation and extension within the form interior, 60 and in positions calculated to dispose the same in desired spaced relation to an exterior face of a wall formed by casting concrete into the form. To this end integrally formed in connection with the spacer element I provide a laterally projecting 65 horizontal flange 26 provided with one or more openings 27 therethrough, three such openings being shown in the drawings by way of illustration. Preferably, although not necessarily, the walls of these openings may be interrupted by gaps or breaks 28, leaving bendable fingers 29 bounding a portion of the peripheries thereof. When such bendable fingers are employed, the size of the openings 27 may be contracted by inward bending of the fingers, so as 70 to reduce the same to fit a rod or bar 30 passed

therethrough, whereby the latter is firmly gripped or clamped by the in-bent finger, and thus securely held in straight up-standing position within the form interior. Ordinarily it is required that reenforcing rods or bars, when employed, 5 be spaced given distances inwardly from an adjacent surface of the wall in which the same are imbedded to serve as reenforcement for the wall. To accommodate my novel rod or bar supporting and holding means to this practice, I 10 extend one end, as 31, of the flange 26 beyond an end of the spacer element 22, so that an outermost opening 27 is provided so located, for example, as to support a bar or rod applied therethrough at a minimum distance of two inches 15 from the form wall, and consequently ultimately at that distance from an exterior face of the wall cast in the form. The remaining openings 27, are spaced ordinarily on one inch centers, so that a selective disposition of the rod or bar 20 more distant from the adjacent form wall may be obtained if desired. It will be understood that the suggested spacing dimensions are, of course, subject to wide variation.

In the use of the novel concrete form and 25 reenforcement retaining means above described, it will be understood that the sleeve members 14-15 may be manipulated, the form walls dismantled, and the tie-rods 13 withdrawn substantially in the manner and with all the advantages fully set forth in my prior United States Letters Patent No. 2,014,080 above referred to. When a unitary or continuous tie-rod, as 13, is employed, and the same is withdrawn 30 from the finished cast concrete, while the spacer element 22 and the supported reenforcing rods or bars 30 are left imbedded in the concrete mass, a transverse opening or hole remains extending through the latter when the tie-rod is withdrawn. This, in some cases, may be 35 found objectionable, if so, I may employ a modified tie-rod and spacer element arrangement as shown, more particularly, in Figs. 5 and 6 of the accompanying drawings. In this modified arrangement, the bore of the spacer element 22 is 40 internally screw-threaded, and in place of the single unitary tie-rod 13, I employ two rods or bolts 32 and 33, each having threaded inner end portions. These rods or bolts 32 and 33 are 45 respectively passed through the respective form 50 walls 10 and associated sleeves, and their inner threaded ends are screwed into the ends of the threaded bore of said spacer element 22, thus 55 uniting the same therewith. The outer ends of the rods or bolts 32 and 33 are provided with 60 the flanged keeper nuts 25 or equivalent or any other suitable means for locking up and retaining the form walls 10 in place as governed by the tying and spacing arrangements. In this 65 case, the spacer element 22 is provided, in its 70 side walls, with upper and lower openings or slots 34, so that when the concrete is poured into the form, the same will flow into the bore of said spacer element, and between the ends of the rods or bolts 32-33, thus plugging or closing up 75 the bore and interrupting any opening extending through the cast concrete mass after the rods or bolts 32-33 are withdrawn. It will be understood that, additional auxiliary spacing sleeves, as 24, may also be used with the above 80 described modified construction, if it is so desired.

While I have shown the spacer element provided with but one perforate flange 26, it will nevertheless be understood that more than one 85

such may be provided and that the spacer sleeve 5 may be disposed to position the same in either horizontal, vertical or angular planes, according to the position in which it may be desired to dispose the reenforcing rods 30 within the form interior.

It is also to be noted that the spacer element or sleeve 22 with its reenforcing rod or bar holding means, as above described, may be applied 10 to an ordinary tie-rod unequipped with the form penetrating sleeves 14-15 or equivalent or similar devices. In such case, any other and independent form wall spreading means, as heretofore commonly known and used in the industry, may be 15 employed, and the element or sleeve 22 merely applied to the tie-rod in desired position between the form walls and used only for its reenforcing rod or bar supporting effect.

I am aware that various changes, other than 20 those specifically mentioned, could be made in the above described constructions and many apparently widely different embodiments of this invention could be made without departing from the scope thereof as defined in the hereinafter 25 claims; hence, it is intended that all matter contained in the above description or shown in the accompanying drawings shall be interpreted as illustrative and not in a limiting sense.

I claim:—

30 1. In concrete form retaining means, in combination, a tie rod engageable through opposed form walls, means mounted on said tie rod for engaging said form walls, a spacer element supported by said tie rod between said wall engaging 35 means, a longitudinally extending flange laterally projecting from said spacer element, said flange having an opening through which a concrete reenforcing rod may be passed so as to be supported within the form interior preparatory to 40 pouring concrete thereinto, and a bendable clamping finger connected with said flange contiguous to said opening and adapted to be bent into gripping relation to the reenforcing rod entered through said opening.

45 2. In concrete form retaining means, in combination, a form tie means engageable through opposed form walls, form wall penetrating sleeves on said tie means having wall engaging stop means in connection with the form penetrating 50 end portions thereof, a spacer means supported by said tie means intermediate the form penetrating end portions of said sleeves, and means carried by said spacer means to embrace and support concrete reenforcing elements within the 55 form interior preparatory to pouring concrete thereinto.

3. In concrete form retaining means, in combination, a form tie means engageable through 60 opposed form walls, form wall penetrating sleeves on said tie means having wall engaging stop means in connection with the form penetrating end portions thereof, a spacer means cooperative with and intermediate the form penetrating end portions of said sleeves, and a longitudinally extending flange laterally projecting from said spacer element, said flange having an opening through which a concrete reenforcing rod may be passed so as to be supported within the form interior 65 preparatory to pouring concrete thereinto.

70 4. In concrete form retaining means, in combination, a form tie means engageable through opposed form walls, form wall penetrating sleeves on said tie means having wall engaging stop 75 means in connection with the form penetrating

end portions thereof, a spacer means cooperative with and intermediate the form penetrating end portions of said sleeves, a longitudinally extending flange laterally projecting from said spacer element, said flange having an opening through 5 which a concrete reenforcing rod may be passed so as to be supported within the form interior preparatory to pouring concrete thereinto, and a bendable clamping finger connected with said flange contiguous to said opening and adapted 10 to be bent into gripping relation to the reenforcing rod entered through the latter.

5. In concrete form retaining means, in combination, a form tie means engageable through opposed form walls, form wall penetrating sleeves 15 on said tie means having wall engaging stop means in connection with the form penetrating end portions thereof, a spacer means cooperative with and intermediate the form penetrating end portions of said sleeves, a longitudinally extending 20 flange laterally projecting from said spacer element, and said flange having a plurality of longitudinally spaced openings to selectively receive a concrete reenforcing rod passed therethrough so as to be supported within the form interior 25 preparatory to pouring concrete thereinto.

6. In concrete form retaining means, in combination, a form tie means engageable through opposed form walls, form wall penetrating sleeves on said tie means having wall engaging stop 30 means in connection with the form penetrating end portions thereof, a spacer means cooperative with and intermediate the form penetrating end portions of said sleeves, a longitudinally extending flange laterally projecting from said 35 spacer element, said flange having a plurality of longitudinally spaced openings to selectively receive a concrete reenforcing rod passed therethrough so as to be supported within the form interior 40 preparatory to pouring concrete thereinto, and bendable rod clamping fingers connected with said flange contiguous to said openings.

7. In a concrete form comprising opposed form walls and a tie-rod extending therebetween, a 45 sleeve means supported on an interior portion of said tie-rod, said sleeve means having a laterally projecting perforate flange through which a concrete reenforcing rod may be passed so as to be supported within the form interior preparatory to 50 pouring concrete thereinto.

8. In a concrete form comprising opposed form walls and a tie-rod extending therebetween, a sleeve means supported on an interior portion of said tie-rod, said sleeve means having a longitudinally extending laterally projecting flange, and said flange having a plurality of longitudinally spaced openings to selectively receive a concrete reenforcing rod passed therethrough so as to be supported within the form interior 60 preparatory to pouring concrete thereinto.

9. In a concrete form comprising opposed form walls and a tie-rod extending therebetween, a sleeve means supported on an interior portion of said tie-rod, said sleeve means having a longitudinally extending laterally projecting flange, and said flange having a plurality of longitudinally spaced openings to selectively receive a concrete reenforcing rod passed therethrough so as to be supported within the form interior 65 preparatory to pouring concrete thereinto, and bendable rod clamping fingers connected with said flange contiguous to said openings.
